[57] CLAIM

The ornamental design for the wall panel for poultry nest structure, as shown and described.

DESCRIPTION

FIG. 1 is a front perspective view of a wall panel for poultry nest structure, showing my new design,

FIG. 2 is a rear perspective, thereof,

FIG. 3 is a front elevational view,

FIG. 4 is a rear elevational view,

FIG. 5 is a side elevational view,

FIG. 6 is a side elevational view of the side opposite that shown in FIG. 5,

FIG. 7 is a top plan view,

FIG. 8 is a bottom view; and,

FIG. 9 is a perspective view, the broken lines showing a poultry nest structure are for illustrative purposes only and form no part of the claimed design.
